UNITED STATES PATENT OFFICE.

STEWART O. DEANE, OF HARRISVILLE, RHODE ISLAND, ASSIGNOR TO DRAPER CORPORATION, OF HOPEDALE, MASSACHUSETTS, A CORPORATION OF MAINE.

LAY SWORD FOR LOOMS.

Application filed August 25, 1927. Serial No. 215,345.

This invention relates to lay swords for looms and has as its object to provide a novel and efficient means for preventing the breakage of the swords when the lay is suddenly stopped before the completion of its swinging movement.

More particularly the object of the invention is to provide such a means for protecting a lay sword from breakage or abnormal strain when the lay "bangs off" or is suddenly stopped in its forward movement, as under the control of the usual protector mechanism commonly employed in looms.

The invention further has as its object to provide such a means at the lower end of the lay sword in the form of a yielding connection with the shaft, thus rendering unnecessary any change in the construction or operation of the parts which act to give the rocking movement to the lay.

These and other objects and features of the invention will appear more fully from the accompanying description and drawings and will be particularly pointed out in the claims.

The invention is applicable to practically any form of loom having a swinging or rocking lay. It is unnecessary, therefore, to illustrate or describe anything more than a portion of one form of loom construction to which the invention may be applied.

In the drawings:

Fig. 1 is a side elevation partially broken away and partially in vertical cross section of the forward left-hand side of an ordinary type of plain loom with a preferred form of the invention embodied therein.

Fig. 2 is a front elevation on a smaller scale of a portion of both lay swords of such a loom and the pivotal shaft therefor showing the invention applied to each.

Fig. 3 is a detail on a large scale of a preferred form of construction in which the invention is specifically embodied.

A loom such as that shown comprises the side frames 1 and 2 connected at the front by the breast beam 3. A lay rocker shaft 4 usually extends across the loom through both frames at the bottom and serves as the pivotal axis for the swinging movement of the lay. The lay 5 is supported upon the lay swords 6 and 7, carried by this shaft 4, one near each side frame of the loom. The lay is given its rocking movement to beat in the filling during the weaving operation by suit-

able pitman connections 8 usually operated from the crank shaft (not shown) of the loom and usually pivoted at 9 at their forward ends to the lay swords.

As is well known to those familiar with the weaving art, it is desirable to provide means for suddenly stopping the swinging movement of the lay and lay swords. Such a sudden stopping of the lay and lay swords is usually necessary when the shuttle fails to complete its flight or to be properly boxed before the filling is beaten in. If the lay beats up under these conditions, a smash occurs and the warps may be broken or the mechanism of the loom damaged. The usual means for stopping the loom is the well known protector mechanism. Such a protector mechanism, in the form illustrated, comprises a rod or shaft 10 mounted on the lay swords and extending across the loom, a finger or arm 11 extending upwardly from this rod and having adjustably mounted in its upper end a stud 12 engaging the rear binder 13 of the shuttle box, and a dagger 14 extending forward and downward from this rod 10. A yielding means such as a spring, not shown, tends to rotate the rod 10 clockwise so as to maintain the stud 12 in contact with the shuttle binder and the dagger 14 in the path of a frog 15 mounted to slide on the loom frame, this frog being retarded in its forward sliding movement by a suitable spring or buffer, not shown. If the shuttle is properly boxed, the binder 13 will be moved thereby rearward and the dagger 14 raised above the path of the frog, but if the shuttle is not properly boxed, the binder will not be moved and the dagger will stand in the path of the frog. Consequently as the lay approaches the end of its forward movement, the dagger engages the frog and the swinging movement of the lay is suddenly stopped, or, as it is said, the loom "bangs off". A slight movement given to the frog upon the stopping of the lay is utilized, as through the knock-off lever 16, to throw the shipper 17 and stop the loom all in a familiar manner. The dagger and frog construction may be provided at one or both sides of the loom.

When the lay is thus suddenly stopped, as to protect the loom in the case of an improperly boxed shuttle, the pitman connections 8 are usually moving forward and upward and as the entire power from the crank

shaft is applied through the pitman connections 8 to the pivotal point 9, which is well above the point where the dagger 14 engages the frog 15, it will be seen that a great strain is placed upon the lay sword or swords. It is impossible to stop the loom instantly and there is a very considerable momentum to the moving parts. It will be seen that with the lower end of the swords held rigidly, 10 with the lay locked by the engagement of the dagger 14 with the frog and with the point 9 forced forward and upward, a heavy twisting strain or turning moment occurs in the sword about a horizontal axis above and 15 parallel with the shaft 4 or pivotal axis of the sword. This strain tends both to bend the sword and to elongate it. The result is that lay swords are very frequently broken under these conditions.

20 The present invention provides a give-way connection at the lower end of the lay sword which permits the lower end to move with respect to the shaft 4 or the pivotal axis when an abnormal strain of the character described takes place and to move sufficiently to prevent breakage of the sword. Since the lower end of the sword is a relatively long distance away from the pivotal point 9 and the point where the dagger engages the frog, 25 a very slight movement at the lower end is sufficient to counteract this abnormal strain. Furthermore, by providing a give-way connection at this point, no change whatever is necessary in the driving connections between the crank shaft or other driving element and the lay. This is important because these connections may thus be made permanently and accurately to insure the proper beating in movement of the lay and 30 may remain unaltered. Any looseness or maladjustment in the connections between the crank shaft and the lay, especially when weaving certain classes of goods, may result in injury to the goods by preventing uniformity and accuracy of the beating in of 35 the filling.

40 Furthermore, it has been found in practice that breakage of the lay swords usually occurs just above the shaft 4 or just above the point where the strain is relieved by the present invention.

In the preferred form of construction illustrated, the lower end of the lay sword is provided with a vertically split bearing engaging the shaft 4 and by "vertically split" 45 it is meant that the bearing is so split that when the lay sword yields or moves with respect to its pivotal axis, it will move in a substantially horizontal direction and, in the form illustrated, in a horizontal rearward direction.

50 In the form illustrated, the lower end of the sword 6 is provided with a semi-circular recess 18 to fit the shaft 4 and a cap 19 having a cooperating semi-circular recess 20 is

secured to the sword by a series of bolts 21, herein shown as two in number. Upon these bolts are mounted helical compression springs 22 between the cap 19 and washers 23 and lock nuts 24.

55 It will be noted that, with the usual construction of loom illustrated, it is necessary, to protect the sword, that the lower end shall move rearward. Consequently the sword extends downward to the rear of the shaft 4 and the cap 19 is placed at the front of the shaft 4. When, therefore, the loom is suddenly stopped or bang-off occurs and an abnormal horizontal twist or turning moment in the sword is thus caused at the upper 60 end thereof, the springs 22 yield and the lower end of the sword moves rearward in a horizontal direction to a slight degree, as shown in Fig. 1. By providing springs 22 of proper strength and number and by adjusting the nuts 24, this yielding movement may be adjusted to the degree necessary to prevent any breakage of the swords due to this abnormal strain.

70 The construction is shown in detail applied to the lay sword at the "live frog" side of the loom but, as indicated in Fig. 2, may be applied to the swords at each side of the loom.

75 It is found in practice that looms equipped with this invention may be run at a much higher speed without danger of breaking the swords when bang-off occurs. The production of the looms is therefore materially increased, the expense and loss of time involved in replacing broken swords is eliminated, the accurate adjustments of the connections for operating the lay are unimpaired, and accuracy of beat-up is maintained all by this invention.

80 Having thus described the invention, what is claimed as new, and desired to be secured by Letters Patent, is:

85 1. In a loom, a shaft, a lay sword having at its lower end a vertically split bearing 90 engaging the shaft, bolts above and below the shaft connecting the bearing parts, and springs on said bolts acting to clamp said bearing parts together and to permit separation of the bearing parts and a consequent 95 horizontal movement of the lower end of the lay sword.

100 2. In a loom, a shaft, a lay sword extending at its lower end to the rear of said shaft, and means for yieldingly clamping said lower end to said shaft, whereby the lower end of the sword may move rearward slightly 105 to protect the sword against undue strain or breakage upon the occurrence of an abnormal, horizontal twisting strain at the upper end of the sword.

110 3. In a loom, a lay, a shaft, lay swords supporting the lay and mounted at their lower ends on said shaft, one of said swords having a vertically split bearing engaging 115

said shaft, and yielding means for clamping said bearing parts together and for permitting said bearing parts to separate upon an abnormal twisting movement being given to 5 the lay.

4. In a loom, a lay sword pivotally mounted at its lower end, and means acting normally to hold the lower end of the lay sword in fixed rotary relation to its pivotal axis 10 and further acting, upon the occurrence of an abnormal turning moment at the upper end of the sword, to permit the lower end of the sword to swing horizontally away from said pivotal axis.

15 5. In a loom, a lay sword mounted to swing forward and rearward about a pivotal axis at its lower end, and means acting normally to hold the lower end of the lay sword in fixed rotary relation to its pivotal

20 axis and further acting upon the occurrence of an abnormal twist applied to the sword about an axis above and parallel to the pivotal axis tending to move the upper end of the sword forward, to permit the lower end 25 of the sword to swing rearward away from the pivotal axis.

6. A loom comprising a frame, a lay, a shaft, lay swords supporting the lay and mounted at their lower ends on the shaft, a 30 protector dagger connected to one of the lay swords and engaging the frame when the forward movement of the lay is to be stopped, means for rocking the lay swords connected thereto above the point of connection of the protector dagger, and yielding means, at the lower end of the lay sword to 35 which the protector dagger is connected, acting to permit the lower end to move rear-

ward when the protector dagger engages the frame and an abnormal horizontal twist is 40 thus given to the upper end of the lay sword.

7. A loom comprising a frame, a lay, a shaft, lay swords supporting the lay and mounted at their lower ends on the shaft, 45 means for rocking the lay forward and backward about the axis of the shaft and for stopping the forward movement of the lay before its completion when required, said means acting when the lay is thus stopped to 50 give an abnormal twist to one of the swords about an axis above and parallel to the shaft tending to move the upper end of the lay forward, and yielding means at the lower end of the lay acting to permit 55 the said lower end to move rearward with respect to the shaft upon the occurrence of the said abnormal twist.

8. A loom comprising a frame, a lay, a shaft, lay swords supporting the lay and mounted at their lower ends on the shaft, 60 means for rocking the lay forward and backward about the axis of the shaft and for stopping the forward movement of the lay before its completion when required, said means acting when the lay is thus stopped to 65 give an abnormal twist to both the swords about an axis above and parallel to the shaft tending to move the upper ends of both swords forward, and yielding means at the lower ends of both swords acting to permit 70 the said lower ends to move rearward with respect to the shaft upon the occurrence of the said abnormal twist.

In testimony whereof, I have signed my name to this specification.

STEWART O. DEANE.
